US00D959251S

(12) **United States Design Patent** (10) Patent No.: **US D959,251 S**
(45) Date of Patent: **** Aug. 2, 2022**

(54) **SLIDE CLIP**

(71) Applicant: **Clarkwestern Dietrich Building Systems LLC**, West Chester, OH (US)
(72) Inventors: **Gregg Allan Stahl**, Lebanon, OH (US); **Brett Daniel Hironimus**, Beaver Falls, PA (US)

(**) Term: **15 Years**(21) Appl. No.: **29/743,534**(22) Filed: **Jul. 22, 2020**(51) LOC (13) Cl. **08-05**

(52) U.S. Cl.

USPC ..... **D8/382**; D25/199(58) **Field of Classification Search**USPC D8/349, 354, 355, 371, 373, 380, 381,

CLAIM

The ornamental design for a slide clip, as shown and described.

DESCRIPTION

FIG. 1 is a front perspective view of a slide clip showing our new design;

FIG. 2 is a rear perspective view of the slide clip of FIG. 1; FIG. 3 is a front elevational view of the slide clip of FIG. 1;

FIG. 4 is a rear plan view of the slide clip of FIG. 1;

FIG. 5 is a left elevational view of the slide clip of FIG. 1;

FIG. 6 is a right elevational view of the slide clip of FIG. 1;

FIG. 7 is a top plan view of the slide clip of FIG. 1;

FIG. 8 is a bottom plan view of the slide clip of FIG. 1;

FIG. 9 is a perspective assembly view of the slide clip of FIG. 1 installed in an exemplary building structure;

FIG. 10 is a front perspective view of a second embodiment of a slide clip showing our new design;

FIG. 11 is a rear perspective view of the slide clip of FIG. 10;

FIG. 12 is a front elevational view of the slide clip of FIG. 10;

FIG. 13 is a rear elevational view of the slide clip of FIG. 10;

FIG. 14 is a left elevational view of the slide clip of FIG. 10;

FIG. 15 is a right elevational view of the slide clip of FIG. 10;

FIG. 16 is a top plan view of the slide clip of FIG. 10;

FIG. 17 is a bottom plan view of the slide clip of FIG. 10;

FIG. 18 is a perspective assembly view of the slide clip of FIG. 10 installed in an exemplary building structure;

FIG. 19 is a front perspective view of a third embodiment of a slide clip showing our new design;

FIG. 20 is a rear perspective view of the slide clip of FIG. 19;

FIG. 21 is a front elevational view of the slide clip of FIG. 19;

FIG. 22 is a rear elevational view of the slide clip of FIG. 19;

FIG. 23 is a left elevational view of the slide clip of FIG. 19;

FIG. 24 is a right elevational view of the slide clip of FIG. 19;

FIG. 25 is a top plan view of the slide clip of FIG. 19;

FIG. 26 is a bottom plan view of the slide clip of FIG. 19;

FIG. 27 is a perspective assembly view of the slide clip of FIG. 19 installed in an exemplary building structure;

FIG. 28 is a front perspective view of a fourth embodiment of a slide clip showing our new design;

FIG. 29 is a rear perspective view of the slide clip of FIG. 28;

FIG. 30 is a front elevational view of the slide clip of FIG. 28;

FIG. 31 is a rear elevational view of the slide clip of FIG. 28;

FIG. 32 is a left elevational view of the slide clip of FIG. 28;

FIG. 33 is a right elevational view of the slide clip of FIG. 28;

FIG. 34 is a top plan view of the slide clip of FIG. 28;

FIG. 35 is a bottom plan view of the slide clip of FIG. 28; and,

FIG. 36 is a perspective assembly view of the slide clip of FIG. 28 installed in an exemplary building structure.

The slide clip is shown with two symbolic breaks in the length of the second plate of the slide clip. The appearance of any portion of the slide clip between the break lines forms no part of the claimed design. The dimples on the first plate shown in broken lines in FIGS. 1, 2, 5, 6, 9-11, 14, 15, 18-20, 23, 24, 27-29, 32, 33, and 36, the stiffeners on the first plate and in the juncture shown in broken lines in FIGS. 1-36, and the indicator marks on the second plate shown in broken lines in FIGS. 1, 3, 9, 10, 12, 18, 19, 21, 27, 28, 30, and 36 are unclaimed subject matter and form no part of the claimed design. Additionally, the exemplary building structures and fasteners shown in broken lines in FIGS. 9, 18, 27, and 36 are unclaimed subject matter and form no part of the claimed design. Furthermore, the through holes on the second plate shown in broken lines in FIGS. 1-18 are unclaimed subject matter for the embodiments shown in FIGS. 1-18. However, the through holes on the second plate shown in solid lines in FIGS. 19-36 are claimed subject matter for the embodiments shown in FIGS. 19-36. In addition, the embossments included on the second plate shown in broken lines in FIGS. 10-27 are unclaimed subject matter for the embodiments shown in FIGS. 10-27. However, the embossments included on the second plate shown in solid lines in FIGS. 1-9 and 28-36 are claimed subject matter for the embodiments shown in FIGS. 1-9 and 28-36.
